US00D916849S

(12) **United States Design Patent** (10) **Patent No.:** **US D916,849 S**
(45) **Date of Patent:** **** Apr. 20, 2021**

(54) **DISPLAY SCREEN OR PORTION THEREOF
WITH GRAPHICAL USER INTERFACE**

- (71) Applicant: **Apple Inc.**, Cupertino, CA (US)
- (72) Inventors: **Jay Christopher Capela**, Santa Cruz, CA (US); **Anton Davydov**, Gilroy, CA (US); **Alan C. Dye**, San Francisco, CA (US); **Alexander Charles MacLean**, San Jose, CA (US); **Charles Janusz Migos**, Millbrae, CA (US); **Parthiban Mohanraj**, Cupertino, CA (US)
- (73) Assignee: **Apple Inc.**, Cupertino, CA (US)
- (**) Term: **15 Years**
- (21) Appl. No.: **29/725,665**
- (22) Filed: **Feb. 26, 2020**

Related U.S. Application Data

- (63) Continuation of application No. 29/701,241, filed on Aug. 9, 2019, now Pat. No. Des. 878,408, which is a continuation of application No. 29/586,964, filed on Dec. 8, 2016, now abandoned, which is a continuation of application No. 29/565,475, filed on May 20, 2016, now Pat. No. Des. 777,771, which is a continuation of application No. 29/529,434, filed on Jun. 7, 2015, now Pat. No. Des. 764,498.

(57) **CLAIM**

The ornamental design for a display screen or portion thereof with graphical user interface, as shown and described.

DESCRIPTION

The file of this patent contains at least one drawing executed in color. Copies of this patent with color drawing(s) will be provided by the Office upon request and payment of the necessary fee.

The sole FIGURE shows a display screen or portion thereof with graphical user interface showing our new design.

The peripheral broken lines represent a display screen or portion thereof and form no part of the claimed design.
